UNITED STATES PATENT OFFICE.

JULIUS KINDERVATER, OF CLOSTER, NEW JERSEY.

CONNECTING-ROD.

1,347,104.

Specification of Letters Patent. Patented July 20, 1920.

Application filed May 3, 1919. Serial No. 294,415.

To all whom it may concern:

Be it known that I, JULIUS KINDERVATER, a citizen of the United States, residing at Closter, in the county of Bergen and State 5 of New Jersey, have invented certain new and useful Improvements in Connecting Rods, of which the following is a specification.

This invention relates to improvements in 10 the construction of connecting rods and associated parts, and more particularly to connecting rods and parts for use in piston driven pneumatic drills and like tools. A common construction in tools of this type is 15 to provide an arrangement of the cylinders whereby the same are located in the same plane and displaced at an angle to each other, preferably 90°, the connecting rod of each piston of said cylinders being connected at a single point on the crank. It is to 20 this particular type of tool that my invention has reference, although its application is equally well suited for any form of tool or mechanism having reciprocating pistons.

Among the objects of the invention is to 25 provide an improved rod which shall be simple and rugged in construction, cheap to manufacture, and easy to assemble, and which can be readily detached from the crank when occasion requires.

To this end I propose to construct the rod of two wholly separate and independent sections, lying side by side, said sections 30 having at one end integral lateral projections, together forming a transverse journal for connection with the piston, and at the other end provided with enlarged semi-cylindrical portions together constituting a 35 split tubular bearing for the crank. I further propose to so pivot the rod sections to the piston that they may partake of 40 relative swinging movement around a common axis, thus separating the said split bearing so that it may be removed from the crank, and to so construct such bearing on one rod that it serves as a journal for the bearing of the other rod.

In order that the invention may be readily 45 understood, reference is had to the accompanying drawings forming part of this specification and in which:

Figure 1 is a sectional side elevation showing the pair of my improved connecting rods assembled on a common crank;

Fig. 2 is an edge elevation looking from the left of Fig. 1;

Fig. 3 is a plan view of the parts shown in Fig. 1;

Fig. 4 is a transverse section through the 60 crank connection substantially on the line 4-4 of Fig. 3;

Fig. 5 is a perspective view of one of the yokes for attaching the rod to the piston;

Fig. 6 is a transverse section on the line 65 6-6 of Fig. 1;

Fig. 7 is a sectional view taken substantially on the line 7-7 of Fig. 3;

Fig. 8 is a view similar to Fig. 6 but showing a slightly modified construction; 70

Figs. 9 and 10 are sections on the lines 9-9 and 10-10, respectively, of Fig. 8, parts being broken away; and

Fig. 11 is a perspective view of one end of one of the rod sections shown in Figs. 75 8, 9 and 10.

Referring to the drawings in detail, 1 and 2 designate a pair of pistons arranged to work in cylinders, (not shown), disposed at right angles to each other. 3 and 4 designate 80 my improved connecting rods which are attached to pistons 1 and 2 respectively. 5 designates a split bushing, which surrounds the crank to which the connecting rods are secured.

Each of my improved connecting rods is 85 split longitudinally on a central plane so as to form two wholly independent separable sections. The two sections of the rod 3 are secured together by a single screw 7, 90 while the sections of the rod 4 are united by a series of three screws 8, (see Fig. 3).

The connecting rod 4 is Y-shaped in plan as shown in Fig. 3, and the ends of each branch of each section are curved into semi-cylindrical form as indicated at 6. The extreme ends abut as shown at 10 so that the entire structure forms a split tubular bearing having two limbs or branches. 95

The ends of each section of the rod 3 are 100 enlarged to form semi-cylindrical portions 9, the ends of each abutting as at 11 to form a closed tubular bearing. The meeting edges of the semi-cylindrical portions 9 are preferably rabbeted to form overlapping 105 tongues 9^a and 9^b as clearly shown in Fig. 7.

The split tubular bearing formed by the semi-cylindrical portions 9 of the connecting rod 3 is extended transversely to a length or width substantially equal to that 110

of the branches 6 of the connecting rod 4, and is provided at its ends with annular grooves or seats 12, separated by an intervening thickened portion 13 (see Fig. 4).

5 By reference to Figs. 3 and 4 it will be seen that the curved portions 6 embrace the tubular bearing 9 and lie in the grooves 12 formed therein so that the bearing 9 constitutes in fact a journal for the bearing members 6. The split bushing 5 which surrounds the crank lies within the split tubular bearing 9. From this it will be seen that both connecting rods are attached to the crank at the same point, the bearing portion of one 10 rod serving as a journal for and surrounded by the bearing portion of the other rod.

In order to provide means for conveniently attaching the connecting rods to the pistons, each section of each rod is formed 20 at its end with an integral transversely extending portion 14 having a cylindrical outer surface, such portions, when assembled in pairs, as shown in Fig. 1, constituting journals or pivot pins projecting at each side 25 of the respective rods. In order to attach these journals to the respective piston, I provide in each case a pair of yokes 16 having base flanges 17 secured to the piston by means of rivets 19. The yokes 16 are provided at their inner sides with trough-like 30 projections 18, which projections abut as shown in Figs. 2 and 3 to gage the proper spacing of the yokes. It will be understood that in assembling, the yokes are slipped 35 over the ends of the journal 14 and are then riveted to the piston after the parts have been placed in position.

In order to permit the sections of the rods to have relative and independent swinging 40 movement on the journal portions 14, these portions are cut away or beveled at one side beyond the axis thereof as indicated at 15 in Fig. 1. It will therefore be apparent that when the screws 7 or 8 are removed, the two 45 sections of either rod may be swung apart as indicated in dotted lines in Fig. 2 so that the rods may be thus disconnected from the crank. It will therefore be seen that each rod section of any pair is capable of relative 50 pivotal movement about a common axis, such axis being the same as that about which the rod oscillates as a whole when in operation.

In Figs. 8 to 11 inclusive, I have shown a slightly modified construction embodying 55 the same principles. In these views the connecting rod is indicated at 3' and a hollow semi-cylindrical bearing or journal portion 24 is formed integral with and extends transversely of each rod section. A pivot 60 pin 27 extends through the hollow bore 25 of the journal portion 24 and the two sections of the journal and rod are held together and retained in position on this pivot pin by means of a pair of collars 28, sur- 65 rounding the ends of the portions 24. It is

proposed to disconnect the rod from the crank in the same manner as shown in Fig. 1, viz., by swinging the sections apart about their pivotal axis, and to this end the extreme edge of each portion 24 at one side 70 of the axis is cut away or shortened as illustrated at 24^a in Fig. 11, so as to provide a space 26 between the abutting edges, (see Fig. 9). This space permits the two sections to be swung around the pin 27 so as to separate their outer ends sufficiently to clear the crank bushing. 75

In both modifications, however, the same principle of construction is employed, viz., the mounting of the rod sections so that they 80 may have a relative swinging movement about a common pivotal axis to permit the separation of their inner ends. In both cases, also, integral, transversely extending journal portions are formed on the rod sections and these portions are cut away at one side of the pivotal axis so as to permit the above described relative swinging movement. 85

What I claim is:

1. The combination with a piston, of a 90 connecting rod provided at one end with a cylindric portion extending transversely of the rod and forming an integral journal, and means for connecting such cylindric portion to the piston, such means comprising a pair of independent one piece yokes secured to the piston, each yoke completely encircling said cylindrical portion. 95

2. The combination with a piston, of a connecting rod provided at one end with an 100 integral cylindric portion extending transversely of said rod, both said rod and cylindric portion being split longitudinally into two wholly independent separable sections, and means for confining and pivotally connecting the sections of said cylindric portion with the piston, the inner faces of the sections of the cylindric portion on one side of its axis within said confining means being cut away so as to permit the rod sections to 110 be separated by swinging them about said axis. 105

3. The combination with a piston, of a connecting rod provided at one end with an integral enlargement, both said rod and enlargement being split longitudinally into two wholly independent separable sections, and means carried by the piston for embracing and confining the sections of said enlargement, said means serving to pivotally 115 connect the rod and piston, the inner faces of the sections of the said enlargement on one side of its pivotal center being cut away so as to permit the free ends of the rod sections to be separated by swinging them 120 about said axis. 125

4. The combination with a piston and crank, of a connecting rod provided at one end with an integral enlargement, and at the other with a portion shaped to embrace said 130

crank, said rod being split longitudinally into two wholly independent separable sections, a journal member carried by the piston, in which journal member the said enlargement 5 is pivotally received, the sections of said enlargement being confined by said journal member and relatively movable therein about the common pivotal center, whereby the rod may be disconnected from the crank by swinging the rod sections about 10 such center so as to separate the crank embracing ends thereof.

5. The combination with a piston and crank, of a connecting rod therefor, said rod 15 being split longitudinally into two wholly separable sections, said sections being shaped at one end to embrace said crank, and being independently pivotally connected at the other end with said piston so as to 20 be capable of relative, swinging movement about a common axis coinciding with that of said pivotal connection.

6. The combination with pistons and a common crank, of connecting rods joining said pistons with said crank, each of said rods being split longitudinally into two wholly 25 independent sections, each section having an enlarged semi-cylindric portion so as to form a tubular split bearing at one end of each of said rods, the bearing of one of said rods being adapted to be journaled on said crank, and the bearing of the other of said rods being adapted to be journaled on the bearing of the first mentioned rod, and means for pivotally connecting the opposite 30 ends of the pairs of rod sections to said pistons so that the members of each pair may swing relative to the pistons and to each other, said pivotal connecting means being constructed to prevent separation of the rod 35 sections adjacent the pistons. 40

In testimony whereof I affix my signature,

JULIUS KINDERVATER.
